UNITED STATES PATENT OFFICE.

FRED A. PUTNAM, OF KEENE, NEW HAMPSHIRE, ASSIGNOR TO MARKEM MACHINE COMPANY, OF BOSTON, MASSACHUSETTS, A CORPORATION OF MASSACHUSETTS.

TYPE WHEEL.

Application filed April 22, 1922. Serial No. 556,055.

To all whom it may concern:

Be it known that I, FRED A. PUTNAM, a citizen of the United States, and resident of Keene, county of Cheshire, State of New Hampshire, have invented an Improvement in Type Wheels, of which the following description, in connection with the accompanying drawing, is a specification, like characters on the drawing representing like parts.

10. This invention relates to type wheels for use in those printing or marking machines that have a plurality of independently-adjustable type wheels each bearing a plurality of type characters, an example of such marking machine being found in United States Patents No. 1,131,865 and No. 1,131,959, both dated March 16, 1915.

One of the objects of my present invention is to provide a type wheel of this character which is constructed so that the type are separable from the body of the wheel. One advantage of this construction is that if it is desired for any reason to change one or more of the type characters of any type wheel, such change can be effected by simply removing the type characters which are not desired and substituting therefor other type characters. In some type wheels the type characters are cast integral with the wheel 30 and, of course, where this construction is employed the only way to effect a change in one or more of the type characters on the wheel is to provide a new type wheel.

Another advantage which is derived from this construction is that the type characters can be made from a relatively hard material which will withstand the wear to which they are subjected, while the body of the type wheel can be made of a material which 40 while suitable for the body of the wheel might not be suitable for the type characters.

Other objects of the invention are to improve type wheels all as will be more fully hereinafter set forth.

45. In order to give an understanding of the invention I have illustrated in the drawings a selected embodiment thereof which will now be described after which the novel features will be pointed out in the appended 50 claims.

Fig. 1 is a side view of a type wheel embodying the invention.

55. Fig. 2 is a sectional view of one of the type-carrying arms of the type wheel showing the type block in position thereon.

Fig. 3 is a section on the line 3—3, Fig. 2.

Fig. 4 is a perspective view of one of the type blocks removed.

Fig. 5 is a perspective view of the end of one of the type-carrying arms. 60

Fig. 6 is an under side perspective view of the type block.

The type wheel herein shown comprises a body portion 1 which may have any suitable shape depending on the construction of the marking machine with which it is used. This body portion 1 is provided with a plurality of radially-extending arms 2 each adapted to support a type character. The type characters are formed on type blocks 3 which are secured to the ends of the arms 2, and the construction is preferably such that the type blocks 3 can be removed from the arms in order to permit them to be replaced by new type blocks. Each type 75 block has on its outer face a type character 4. These type blocks may be made in any way without departing from the invention. They might be made as die castings or the type characters 4 may be engraved or cut 80 thereon by any suitable means. In any event the material of which the type blocks 3 are made will preferably be hard and strong so that they will stand up under hard and continuous usage. 85

In order to anchor the type blocks 3 to the arms 2 I propose to form in the end of each arm 2 crossing grooves and to provide the type block with corresponding ribs and tongues to fit the grooves. By having the 90 tongues and grooves crossing each other or extending in different directions they serve to anchor the type block in place and prevent it from lateral movement in any direction. 95

In the construction herein each arm 2 is provided with a groove or slot 5 extending transversely thereacross and is also provided with another groove or slot 6 extending thereacross in another direction, preferably 100 in a direction of the plane of the type wheel. One of these grooves is shown as deeper than the other, although this is not essential. In this construction the groove or slot 5 is deeper than the groove 6. 105

The type block 3 is formed with an inwardly-extending tongue 8 of a size to fit the slot 5 and is also provided with a rib 9 of a shape and size to fit the groove 6. The tongue and the rib intersect each other and 110

because the tongue 8 is larger than the rib 9, said rib will appear as two separated sections situated on opposite sides of the tongue 8.

5 Each type block is retained in place by a locking pin 10 which extends transversely through the arm 2, the wall of the slot 5 and one face of the tongue 8 each being provided with a groove 11 to receive the pin. When 10 the parts are assembled the two grooves 11 form an opening extending transversely through the arm into which the pin 10 may be driven.

15 In assembling the type block with the type wheel, said block will be inserted in its place with the tongue 8 fitting into the slot 5 and the rib sections 9 fitting into the groove 6, after which the locking pin 10 will be driven into the aligned grooves 11. The 20 rib sections 9 hold each type block from movement transversely of the arm 2 and the tongue 8 holds the block from movement in a direction tangentially of the wheel.

25 With this construction it is possible to make the body of the type wheel of a relatively cheap metal which, while having all the characteristics necessary for the body of the wheel, does not have the proper characteristics for the type characters, and to 30 make the type blocks of another kind of material which is better suited for making of type characters. In a type wheel having this construction the type characters can be made of a material which will withstand the 35 wear to which they are subjected while the body of the type wheel can be made of a less expensive material. In this way a type wheel of the highest quality, so far as service is concerned, can be produced at 40 relatively small cost.

The type blocks can be made as die castings or may be made of steel which is engraved or cut to form the type characters

thereon or may be made in any other way. The type blocks are all interchangeable so 45 that if it is desirable at any time to change the order of the type characters or to provide different type characters, the type blocks can be readily removed and new ones inserted which will have the proper order 50 or the desired type characters.

While I have illustrated herein a selected embodiment of the invention I do not wish to be limited to the constructional features shown.

55 I claim.

1. A type wheel having a plurality of radial type carrying arms each provided at its end with two crossing grooves, and type blocks carried by said arms and each having 60 tongues and ribs fitting said grooves.

2. In a type wheel, the combination with a body portion having a plurality of radial arms each provided with a slot extending across the end thereof in one direction and a 65 groove extending across the end thereof in another direction, of type blocks carried by said arms, each block having a tongue to fit the slot and a rib to fit the groove, and means for locking the blocks to the arms. 70

3. In a type wheel, the combination with a body portion having radially-extending arms, each having in its end a slot extending transversely thereof and a groove of less depth than the slot extending at an angle 75 thereto, of type blocks carried by said arms each having a tongue fitting the slot and a rib fitting the groove, one wall of each slot and the tongue fitting said slot each having a groove therein, which grooves are aligned 80 when the block is in place, and a locking pin in said aligned grooves.

In testimony whereof, I have signed my name to this specification.

FRED A. PUTNAM.
